THE NORRIS PETERS CO., PHOTO-LITHO., WASHINGTON, D. C.

UNITED STATES PATENT OFFICE.

CAMPBELL JACKSON, OF ABINGDON, VIRGINIA.

ASH-PIT.

SPECIFICATION forming part of Letters Patent No. 593,540, dated November 9, 1897.

Application filed May 19, 1897. Serial No. 637,237. (No model.)

To all whom it may concern:

Be it known that I, CAMPBELL JACKSON, a citizen of the United States, and a resident of Abingdon, county of Washington, and State 5 of Virginia, have invented certain new and useful Improvements in Ash-Pits, of which the following is a specification, reference being had to the accompanying drawings, forming a part thereof, in which similar letters of 10 reference indicate corresponding parts.

My invention relates to an improvement in ash-pits for steam locomotive-engines and the like in which the floor of the pit is made up 15 of sections which revolve, so as to open, and are operated by a lever in the cab of the engine; and the object of my invention is to provide an ash-pit from which the ashes may be readily, effectively, and quickly removed. I attain this object by the device illustrated 20 in the accompanying drawings, which form a part of this application, and in which—

Figure 1 is an end view of a locomotive having the ash-pit attached and showing the lower portion of same in section. Fig. 2 is a 25 sectional elevation through the line *xx*. Fig. 3 is a part elevation and section through the line *yy* and looking in the direction indicated by arrow.

My invention consists, chiefly, of the shell A, 30 forming the outer casing of the ash-pit, the plates *a*, which are pivotally mounted or connected to the lower part of the shell A and form the bottom of the ash-pit, and a series of levers employed to operate the plates *a*.

The shell A is securely fastened under the 35 end of the boiler and cab-floor, as ash-pits in ordinary cases are attached, and it is supplied with a normally-closed rear door A' for use when the swinging plates become clogged.

The plates *a*, which form the bottom of the 40 pit, have the small operating-wheels *a'*, which are securely fastened to the pivot of each plate, projecting through one side of the shell A. A cleat *a''* is fastened to the lower 45 edge of the two sides of the shell and provide bearings for the ends of the plates *a* when the bottom of the pit is closed.

The wheels *a'*, which turn the plates *a* on 50 their pivots, are operated by the lever *b* in conjunction with the lever *b'*, pivoted to the

side of the shell A at *b*². The rods *c* and *c'* are fastened by a pivot connection to the lever *b'* on both sides of the fulcrum *b*². The rods *c* and *c'* are pivotally connected to a secondary lever *c*², which makes connection by 55 means of the rods *c*³ with the operating-wheels *a'*.

The lever *b* is pivotally connected to the lever *b'* at *b*⁴ and has upon its edge a ratchet *d*, which engages with a tooth or lug *d'* in the 60 floor of the cab and is adapted to regulate the opening of the plates *a* in the bottom of the pit.

When an operator desires to open the bottom of the ash-pit to allow any ashes to fall 65 out, he grasps the lever *b*, and pulling upon it he causes the operating-wheels *a'* to turn, thereby turning the plates *a* until they are in an upright position, as shown in Fig. 3, and allowing a tooth of the ratchet *d* to engage in 70 lug *d'* the plates may be kept in the upright position. When the lever *b* is released, the plates *a* will fall back to their normal position.

Having thus described my invention, what 75 I claim as new, and desire to secure by Letters Patent, is—

The combination, in an ash-pit for locomotive steam-engines and the like, of the outer shell or casing A, the bottom plates *a* pivotally mounted in the side of said shell, the operating-wheels *a'* securely mounted on the pivotal projections on one side of the plates *a*, the cleat *a''* employed to normally hold the plates *a* in place, the levers *b* and *b'* employed 80 in conjunction with the rods and levers, *c*, *c'*, *c*² and *c*³ and the wheels *a'* to operate the bottom plates, and the ratchet *d* in the lever *b* engaging with the lug and tooth *d'* in floor of cab and employed to regulate and keep open 85 the aforesaid plates *a*, substantially as shown and described.

In testimony that I claim the foregoing as my invention I have signed my name, in presence of two witnesses, this 14th day of May, 95 1897.

CAMPBELL JACKSON.

Witnesses:

AUGUSTUS WILEY CARMACK,
GORDON EDGAR JOHNSTON.
